UNITED STATES PATENT OFFICE.

ISAAC H. COLLER, OF POUGHKEEPSIE, NEW YORK.

IMPROVEMENT IN HARVESTERS.

Specification forming part of Letters Patent No. 40,675, dated November 24, 1863.

To all whom it may concern:

Be it known that I, ISAAC H. COLLER, of Poughkeepsie, in the county of Dutchess and State of New York, have invented a new and useful Improvement in Harvesters; and I do hereby declare that the following is a full, clear, and exact description of the same, reference being had to the accompanying drawings, forming part of this specification, in which—

Figure 1 is a front elevation of a part of a harvester, showing the operation of my improvement. The dotted lines illustrate how the finger-bar rises to pass over obstacles. Fig. 2 is a plan view of a portion of a harvester. Fig. 3 represents a portion of the left-hand side of a harvester. Fig. 4 represents a portion of right-hand side of harvester. Fig. 5 is a section of a finger-bar and finger.

My invention relates to an improvement in harvesters which are constructed with a finger-bar made without a folding joint, but with an extension running under the frame from the inner shoe. In applying such finger-bars to harvesters it is essential that they be arranged so as to rise and descend automatically as they run over undulating surfaces, and especially that they rise squarely along their whole length with respect to the ground. It also is important to have the means employed to effect this end simple and firm. My improvement secures a nearly-horizontal automatic adjustment, and provides a very simple and strong means for the accomplishment of this result.

In the drawings, A is the frame of a harvester; D, the finger-bar, with an extension, E, wrought upon it or attached to the shoe F, as represented. The extension E forms a support for the shoe F, which in turn supports the finger-bar. G G are the guard-teeth, made of any approved form.

To connect the finger-bar firmly to the frame and still have it rise and fall horizontally, or nearly so, along its whole length or from inner to outer end, I provide links H on the shoe F for finger-bar, and to these links, by means of a hinge-pin, I connect a strong slide or plate, C, this slide standing vertically, or nearly so, to the plane of the finger-beam. In order to guide and control this slide as the finger-beam rises and falls, I pass it up through a strong box, B, which is bolted fast to the frame A, as shown. The slide just fits the box, but is free to move up and down in it.

To govern the extreme end of the extension E of the finger-bar, I provide a slotted guide, K, at the outer side of the frame, (underneath,) and have the said end of the extension E extend through the same, as shown. By thus extending the finger-bar and having it attached to the slide C and connected to the guide K it is converted into a lever of the first order, the fulcrum thereof being a changing or shifting fulcrum. Thus the pressure of cutting the grass on D is distributed over the whole of frame A.

It should be noticed particularly that the finger-bar has no joints in it; also that the slide C is hinged to the upper side of the shoe F or to the finger-bar, so that there is a freedom of motion at the point I sufficient to prevent any bind of the slide in the box B. It will also be observed that the extension E moves longitudinally as well as vertically in the guide K. By this construction and arrangement I obtain all the advantages to be derived from a rigid finger-bar with an extension, and at the same time do not interfere with the automatic floating of the cutting portion thereof over undulating surfaces. Were a joint provided between the extension and the cutting portion of the finger-bar, the utility of the extension, made rigid, would be destroyed, as the strain would come upon the joint; but by having the pivot-joint connection at I between the slide and the shoe or finger-bar the outer end of the finger-bar can rise and fall in passing over undulating surfaces, and in thus rising and falling there will be no bind between the slide C and box B. If the pivot-joint I was not provided, the guard-teeth on the outer end of the finger-bar would run into the ground when the surface was uneven. The vertical play which is allowed the finger-bar if the slide C were affixed rigidly to it, would not allow the finger-bar to float over ordinary undulating surfaces while it is rising bodily, but only to rise and fall bodily or at right angles to the slide C, the result of which would be that in the lower portions of the field, or on the sides of hills, the stubble would be very unevenly cut, and much of the straw would be wasted. Again, if only the joint I were provided, and the slide C not automatic in its adjustments, the horizontal adjustment could not be obtained during the cutting operation and without stopping the machine. The slide C

and the joint at I allow of two independent motions, with a stiff or jointless finger-bar—i.e., a vertical motion and an undulating motion, the extent of which latter is controlled by the length of the vertical slot in the plate K. This plate K serves two very important offices in the operation of the machine, to wit: It serves as a stay-plate for sustaining the finger-bar, by means of the extension E, against any backward thrust, and thus making the strain come upon the draft-frame equably. It also at the same time allows the finger-bar to have all the vertical movement necessary to success with a reaping or mowing machine.

In using my improvement I suspend the cutting apparatus by a chain, which passes over a pulley on the frame and attaches to an adjusting-lever, as commonly practiced with floating finger-bars.

I am aware that finger-beams with an extension fitting or playing in a slotted plate are new. I also am aware that devices for adjusting the finger-bar squarely or at right angles to the side of the frame have been devised;

but these devices make a positive and unchanging set in the finger-bar after the adjustment is made. I also am aware that jointed finger-beams with an extension and guides or slides have been devised. I therefore make no claim to such contrivances specifically; but

What I do claim as my invention and as a new and useful improvement in harvesters is—

1. The combination of the rigid finger bar D E, binged slide C, and guides B K, the whole constructed and operating substantially as herein described.

2. The slide C, with its box B, when the slide is hinged to the finger-beam or shoe by means of links H and a bolt, I, substantially as herein described.

3. The combination of the slide C, rigid finger-bar D E, shoe F, and hinge-links H, substantially as and for the purpose described.

ISAAC H. COLLER.
